(57) **CLAIM**

The ornamental design for a coat rack stand, as shown and described.

DESCRIPTION

FIG. 1 is a front, right side perspective view of a coat rack stand, showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof;

FIG. 9 is an enlarged view of the selected portion 9 in FIG. 1; and,

FIG. 10 is an enlarged view of the selected portion 10 in FIG. 1.

The dash-dash broken lines in the figures illustrate portions of the coat rack stand that form no part of the claimed design. The dash dash long dash broken lines in FIGS. 1, 9 and 10 represent the bounds of the enlargement taken from FIG. 1 and forms no part of the claimed design.

1 Claim, 10 Drawing Sheets
